SUSPENSION LINK FOR CENTRIFUGAL EXTRACTOR CASINGS

Frank O'Conor, Moline, Ill., assignor to American Machine and Metals, Inc., New York, N. Y., a corporation of Delaware

Application October 20, 1950, Serial No. 191,103

3 Claims. (Cl. 248—18)

1

The invention relates to that type of centrifugal extractor in which liquid is extracted from material contained in a basket revolving on a vertical shaft supported in a casing which is suspended at a number of points around its circumference from pedestals. This permits any unbalance in loading the basket to cause the casing itself to vibrate. The weight of the casing tends to reduce the amplitude of the vibration, and the suspension prevents the transmission of the vibration to the building in which the centrifugal operates. Generally the casing is suspended at three points from pedestals rising from the floor by some form of links which are free to act as a pendulum. Although the suspending link is essentially a pendulum, it must meet exact requirements. The invention provides means for more fully meeting these requirements than links hitherto provided.

Since it is impossible to load the material into the basket so that the weight is distributed around the spindle with absolute uniformity, the extractor will normally operate with an unbalanced load.

If we assume that this unbalanced load is uniformly distributed along a vertical line on one side of the basket, the lower end of the suspension will describe a small circle. Since the upper end and the lower end of the suspending links are held vertical, this creates flexure in the suspension.

The actual motion of the lower end of the suspension is not as simple as indicated. Frequently the extractor armature is driven by a motor attached to one side of the casing. Since the motor armature is in balance, conditions are no longer symmetrical about the axis of rotation of the basket and the path reversed by the lower end of each suspension link will be different. Frequently the three pedestals are spaced unevenly around the side of the casing in order to better support the weight of the motor attached to one side of the casing. This also complicates the motions of the lower end of the suspension links and makes the motions of the several links different. Further complications are introduced when the brake is applied. The brake being attached to the casing, the basket creates a force tending to swing the lower end of each suspension tangential to the casing.

Further complications provided by the fact that the unbalanced load is not necessarily distributed uniformly along one side but a portion of the unbalance may be on one side of the basket near the bottom while the rest of the unbalance may be near the top on the opposite side of the

2

basket. This creates a dynamic unbalance which creates an upward force on the suspension lugs that transmit the weight of the basket and the casing to the suspension links. If this upward force is stronger than the downward force created by that portion of the weight carried by that particular link, there is a tendency for the lower link to be pushed upward. As this happens once in each revolution, there is a very unpleasant sound and corresponding wear upon the suspension link. Since the weight on these suspension links closest to the driving motor which is supported on one side of the casing is different than that on the other link, it will be apparent that although the three links at first sight have to meet identical requirements, and though it might seem as if they were simple pendulums, the requirements are much more complex.

It has been found that a vertical bolt with a ball and socket support at both ends will crystallize and break, especially if lubrication on the ball and socket joints is not maintained. Similarly, a short length of wire rope firmly crystallize and break, especially if lubrication on lower end in the lug, on the extractor will fray. Chains will wear rapidly where one link rests upon the other.

The measure of a well designed extractor is the amount of unbalance which it can carry without excessive sway. The invention provides an extractor which will carry a greater degree of unbalance than has hitherto been possible by providing a link, which in its preferred form allows an unrestricted pendulum action within narrow limits by using a chain for suspension but encasing the chain in a container which is filled with grease. This need not be renewed during the life of the suspension and thus it assures permanent lubrication. The link is further provided with an element acting as a strut which will prevent any upward tendency from lifting the load completely off the links and thus prevent "jumping." Finally the invention recognizes that the combination of the various stresses upon each link is different and provides adjustable means for restraint which becomes increasingly effective as the amplitude of swing at the lower end of each link increases.

In actual test, an extractor 54 inches in diameter designed to carry a load of 400 pounds laundry dry weight at 750 revolutions per minute and able to carry an unbalanced load of 10 pounds placed near the rim of the basket at the top was able to carry 12.5 pounds after the links which form the subject of this invention were installed.

Applicant is the first to provide a chain suspen-

sion which is provided with biasing means that permits adjusting the functioning of each chain suspension to the conditions arising at that particular suspension point.

The object of the invention is to provide a chain suspension for a centrifugal extractor surrounded by a tubular strut preventing the extractor from jumping and retaining the lubricant in which the chain links are embedded.

A further object of the invention is to provide a tube which is adapted to surround the chain links on which an extractor is suspended having cupped shaped ends pressing against flexible washers which, under the pressure, expand against both the edge of the cup and the anchor bolt thus preventing loss of lubricant.

Still another object of the invention is to provide a chain suspension for an extractor housing surrounded by a tubular strut having cup shaped ends which bear against washers and means at one of the supports suspending the chain for compressing the flexible washers between which the tubular strut is located to the extent desired.

Fig. 1 is an elevation of a centrifugal extractor which incorporates the invention.

Fig. 2 is an enlarged vertical section through a suspension post showing the suspension in detail.

Fig. 3 is a plan view of the top of a pedestal with the cap removed showing the plate from which the chain is suspended and the screws for regulating the pressure on the tubular strut and the flexible washers.

Fig. 4 is a cross section along the line 3—3 in Fig. 2.

The typical extractor shown in Fig. 1 has a tub shaped housing 1 which may be closed by a cover 45. Supported in the base of this housing is a vertical shaft 5 which supports an extractor basket (not shown) within the housing and a pulley 6 below the housing. Attached to one side of the housing is a bracket 7 which supports the motor 8. The motor shaft carries a drive pulley 10 which is connected to the extractor pulley 6 by belts 11.

Spaced around the circumference of the circular housing are three lugs 2 each of which is suspended from a pedestal 3 in a manner more fully described below.

The enlarged vertical section through a pedestal shown in Fig. 2 shows the invention more completely. A top view of the pedestal shown in Fig. 2 with the cap removed is shown in Fig. 3. As shown in these views, each pedestal may consist of a bent piece of boiler plate 13 set on edge to form a hollow post open on the side toward the extractor housing. To the upper end of this post is attached a crescent shaped plate 14 which may have upstanding edges 15 which locates the cap 12. The cut away portion 16 permits the suspension to extend up to the suspension plate 27 which rests on the top of the plate 14 and is attached thereto by a number of screws 29. The cap covers the upper end of the anchor bolt and the adjusting screws related thereto.

At 34 the suspension plate is drilled for the reception of the stem 21 of the anchor bolt. The suspension chain 17 is attached to the anchorage ends of the anchor bolt 18 by a pin 19. In a similar manner an anchor bolt is attached to the lower end of the chain and bolted to the flat part 28 of the channel shaped lug 2. The upper anchor bolt may be drilled axially as shown at 22 to permit supplying grease to the inside of the suspension through the grease fitting 23. A metal

washer 24 is slipped over each of the anchor bolts 18. A washer 25, made of resilient material bears against the metal washer 24. A suspension chain 17 is surrounded by a metal tubular strut 30 which has cup shaped ends which consist of a horizontal disc 31 surrounded by a cylindrical flange 32. Ribs 33 may be provided to secure greater stiffness in these outwardly extending cup shaped ends of the tubular struts. One of the resilient washers 25 fits snugly into each of these cylindrical extensions 32. Nuts 26 fitted on a threaded end of the anchor bolt bear against the suspension plate 27 at the top and against the horizontal portion 28 of the lug at its lower end and permits drawing the shoulder 20 on the anchor bolt snugly against the support.

Three screws 35 each provided with a lock nut 36 are symmetrically placed relative to the anchorage end 18. The more said three screws are turned downward, the harder the plate 24 will press against the resilient washer 25. This pressure will be transmitted from the upper resilient washer through plate 31 to the tubular strut 30 and thence to the corresponding element at the lower end of the suspension assembly. By referring more specifically to Fig. 2, it will be evident that the machine can jump vertically only to the extent that it can compress the two resilient washers.

As each of these washers is compressed it will expand laterally and in so doing it will bear with increasing intensity against the upstanding flange 32 and the sides of the anchor bolt 18. Thus, leakage of grease along the edges of the tubular strut or bolts is prevented.

It will be evident that if the extractor gyrates slightly the lower anchor bolt moves within a small circle. In this case, the presence of the strut surrounding the chain will impose no restraint on the movement. But if the movement becomes larger, the restraint created by the combination of the strut, its flanges, and the resilient washers will increase. Thus, by proper adjustment of the screws 35 the desired degree of restraint may be effected.

I claim:

1. A suspension assembly for a centrifugal extractor having lugs and hung from pedestals with slotted tops, comprising, a slotted plate bolted to the top of the pedestal, a shouldered anchor bolt drawn up against the under side of said plate, another shouldered anchor bolt drawn up against the top of a lug projecting from the extractor, a chain extending from one of said anchor bolts to the other, a tubular strut surrounding said chain, outwardly extending horizontal flanges at the ends of said strut, resilient washers on said anchor bolts bearing against said flanges, a flat metal washer on the anchor bolt mounted in said plate, and means accessible from the top of said plate for forcing said metal washer along the anchor bolt to compress the flexible washers against said strut and the lug.

2. In a centrifugal extractor, in combination, an extractor housing having three laterally projecting horizontal lugs, three pedestals of U-shaped section the open side facing said extractor and one of said lugs projecting into said open side, a horizontal plate at the top of each pedestal, a chain extending from each of said lugs to one of said plates to allow the centrifugal housing to sway horizontally, a tubular strut surrounding each chain, resilient washers at each end of said strut, a metal washer above the upper resilient washer, and three screws passing

through said plate for urging said washers against the strut and the lug to restrain the freedom to sway of said extractor housing.

3. In a centrifugal extractor, in combination, an extractor housing having at least three laterally projecting lugs, at least three pedestals of U-shaped section, each section having an open side facing said extractor and one of said lugs projecting into said open side, a plate at the top of each pedestal, a chain extending from each of said lugs to one of said plates to allow the centrifugal housing to sway horizontally, a tubular strut surrounding each chain, resilient washers at each end of said strut, a metal washer above

the upper resilient washer, and a plurality of screws passing through said plate for urging said washers against the strut and the lug to restrain the freedom of sway of said extractor housing.
